VENTILATING SKYLIGHT

William E. Morrison and Phillip Painter, Indianapolis, Ind., assignors to Jenn-Air Corporation, Indianapolis, Ind., a corporation of Indiana

Filed Apr. 21, 1966, Ser. No. 1,963

Term of patent 7 years

(Cl. D23—153)

Fig. 1.

Fig. 2.

Fig. 3.

FIG. 1 is a side view of a ventilating skylight embodying our new design.

FIG. 2 is a perspective view of the structure shown in FIG. 1.

FIG. 3 is a further perspective view of the structure taken from a more elevated angle than that of FIGURE 2 and showing the damper blades in an open position.

The dominant features of our design reside in the portions shown in full lines, said portions being further characterized by the specific appearance of the pivotal damper doors located on each side of the unit together with the corner located supporting post and in combination with the peripheral drainage channel integral with the skylight dome as shown.

The two sides of the structure not visible in the drawing are identical to the two sides shown.

We claim:

The ornamental design for a ventilating skylight, as shown and described.
